Inventor:
W. H. Houston

UNITED STATES PATENT OFFICE

WILLIAM HOUSTON, OF HAVERHILL, MASSACHUSETTS

PIE PLATE ATTACHMENT

Application filed July 22, 1930. Serial No. 469,714.

This invention relates to certain improvements in pie-plate attachments of the type which consists of a metal ring adapted to be removably mounted on the rim of the plate, and which are primarily advantageous in making pies having a soft filling to hold the dough, which is built up on the plate rim, in place until the pie has been baked, after which the ring is removed.

10 More particularly the invention relates to certain improvements on the particular device disclosed in my Patent No. 1,699,239, dated January 15th, 1929, which was primarily an improvement over prior devices for this purpose, in that it was adapted to be produced by passing a strip of thin sheet metal between suitably shaped die rolls, without rupturing the metal, so that the manufacturing cost was greatly reduced as compared

15 with prior devices.

While the device of said patent may be produced at a low manufacturing cost, the results secured from its use were found to be unsatisfactory, in that flutes or crimps secured in the rim of the pie crust built up against it were not of sufficient depth throughout, and also because the construction did not sufficiently allow for variations from a supposed standard in the diameters of the

20 plates, which in practice vary quite materially, so that unless the ring fitted the plate rim very closely, the dough would be pressed out between the ring and the plate rim, making the results secured so unsatisfactory as to preclude its use.

25 The primary objects of my present invention are to provide a construction which will have all of the advantages of economy of manufacture of the construction disclosed in my said patent, and, in addition, will enable the formation of a device of this character from a single strip of metal, without causing fracture thereof, which will cause the rim of the pie to be crimped in such a manner that the flutes thereof will be of uniform depth and their sides will extend approximately vertically, and the construction will be such that substantial variation in the diameter of the plate from a standard will be permitted.

I accomplish these objects by means of the construction hereinafter described and as illustrated in the accompanying drawings in which:

Fig. 1 is a plan view of a device embodying my present invention, duplicate portions being indicated by dotted lines. 55

Fig. 2 is a side elevation of a section thereof.

Figs. 3 and 4 are sectional views at lines 3— 60
3 and 4—4 respectively of Fig. 2.

According to my present invention, I provide a strip *a* of thin metal of a suitable uniform width, which is adapted to be bent or molded into the form, now to be described, 65 by passing the same between one or more pairs of die rolls, after which the strip is bent into circular form and its ends are lapped and connected to form a ring.

In accordance with my present invention, 70 the strip is molded transversely to provide a cylindrically shaped edge portion *b*, from which an intermediate transversely semi-circular bead *c*, projects outwardly so that the external diameter of the bead is substantially greater at its middle portion than the external diameter of the edge portion *b*. The top side portion of the beads opposite the portion *b*, is extended inward at right angles to, and for a substantial distance within 75 said portion *b*, forming a seating portion *d* and then the edge portion *e*, beyond the seating portion, is bent upwardly therefrom at approximately right angles thereto, and is fluted to provide a regular series of alternating 80 external and internal transversely concave cavities of approximately uniform depth throughout, the sides of which are approximately perpendicular to the seating portion *d*. The flutes are so arranged with 85 reference to the cylindrical edge portion *b* that the internal cavities open to the under side of the seating portion at a distance within the inner surface of said edge portion, as shown in Fig. 4. 90

The strips are preferably cut in suitable lengths before being passed between the die rolls, and the action of the latter tends to bend the strip into circular form, so that the ring is readily formed by overlapping the 100

end portions of the strip and spot welding, or otherwise connecting them together, as shown in Figs. 1 and 2. The internal diameter of the cylindrical portion *b* is made to correspond to a standard diameter of a plate rim, as *h*, so that it may be readily placed thereon until its seating portion rests on the top side of the plate rim, as indicated in Fig. 3, in which position the fluted portion *c* will 10 extend approximately vertically, although preferably this portion will be formed to extend inwardly at a slight inclination, to permit ready removal after the baking operation has been finished.

15 This is not, however, a vital necessity, as in baking the dough usually shrinks sufficiently to permit removal if the sides of the flutes are vertical.

20 As the bottoms of the internal cavities open to the bottom side of the seating portion *d*, within the internal outline of the cylindrical portion *b*, a substantial seat for engagement with the plate rim will be provided between the bottoms of said internal 25 cavities and the extreme edge of the plate rim, so that, when the dough is built up against the inner side of the ring, there will be no opportunity for leakage of the dough over the rim of the plate, and by having the 30 seating portion of substantial width, rings of the same size will be adapted for use on plates which vary somewhat in diameter at their rims.

35 The bead *c* is advantageous in that it improves the article by substantially increasing its stiffness, and preventing it from becoming misshapen, or from being bent so as to cause eventual breakage.

40 The bead *c* is further particularly advantageous in that it permits the formation of flutes of substantially uniform depth in approximately perpendicular relation to the seating portion *d*, without causing rupture of the metal, by means of the rolls, between 45 which the strip is passed, as by forcing the metal outwardly from the edge portion *b* in a reversely curved formation before the opposite edge portion is drawn inward, bent right angularly and fluted. The strain on 50 the metal at the middle portion of the strip is relieved sufficiently to prevent breakage.

55 In practice a strip of double width is passed between two pairs of oppositely disposed die rolls, so that the cylindrical edge portions *b* are formed from the middle portion of the strip, which is split at its middle line, so that two rings are formed simultaneously.

60 It will be understood that while the fluted portion is shown as formed in approximately right angular relation to the seating portion, it may be slightly inclined inwardly without departing from the invention.

I claim:

65 1. A pie plate attachment comprising a continuous strip of metal bent in circular

form and having its ends joined to form a complete ring, one edge portion of the ring being formed cylindrically and adapted to be removably fitted upon the plate rim from its top side, the intermediate portion thereof being extended outward from said edge portion and then reversely inward within said edge portion to form a seating portion and the opposite edge portion within said seating portion being bent right angularly thereto and fluted.

70 2. A pie plate attachment comprising a continuous strip of metal bent into circular form and having its ends joined to form a complete ring, said ring having one edge portion formed cylindrically and adapted to be removably fitted upon the plate rim from the top side, and having a transversely semi-circular bead extending outwardly from said cylindrical portion, the opposite portion of said bead from said portion being extended inwardly beyond said portion, to form a seat for engagement with the top side of the plate rim, and the opposite edge portion of the strip within said seat being extended right angularly upward therefrom and fluted to provide alternating external and internal transversely concave cavities of approximately uniform depth.

75 In testimony whereof, I have signed my name to this specification.

80 WILLIAM HOUSTON.
